REVOLVING CONE MIXER

Elvin M. Underwood, East Liverpool, Ohio, assignor to The Patterson Foundry & Machine Co., East Liverpool, Ohio, a corporation of Ohio

Application March 25, 1939, Serial No. 264,225

2 Claims.

(Cl. 259—96)

My invention relates to an improvement in revolving cone mixers.

The object is to provide a mixer of this general type for completely and uniformly mixing liquid and semi-liquid solutions with the employment of a minimum number of mechanical parts, and in a minimum length of time, by creating circulatory currents and cross-currents throughout the solution, with the purpose in view of reaching every particle with comparative rapidity and all areas substantially alike of the tank in which the material is held while under treatment.

It has been found in practice, when desirable to introduce gas or air underneath the lowermost cone, the air or gas has a tendency to pass up along the shaft and issue at the upper end of the top cone in spite of the downward flow of the liquid at that point, and to obviate it this present invention includes a baffle which is located at some point on the shaft usually equidistant between the discharge ends of the two cones, but not necessarily at that point as will be herein-after indicated, the baffle or baffles acting as a divider to divert the liquids and/or gases into the flowing stream leaving the cones.

In the accompanying drawings:

Figs. 1, 2 and 3 are sectional views showing slightly different forms of cones with a centrally located baffle;

Fig. 4 is a view showing two baffles, one being located within each cone;

Figs. 5, 6 and 7 illustrate different forms of baffles; and

Fig. 8 is a top plan view.

The numeral 1 represents the usual tank in all forms illustrated, and the numeral 2 a rotary shaft common to all forms, and to which both cones and baffles are secured.

Referring to Fig. 1, numerals 3 and 4 represent cones of uniform dimensions secured at their smaller ends to the shaft 2, whereby to rotate with it, with their larger ends discharging toward each other.

A baffle 5 in the form of a disk is secured to the shaft midway between the discharge ends of the cones, and acts as a divider and diverts any air or gas horizontally in all directions into the discharging streams of liquid which meet at the edges of the baffle on their way out between the cones. In other words, the baffle is a divider to divert gases and the liquid into the flowing stream leaving the cone.

It is understood, of course, that the liquid is sucked in through the inlets 6 and 7 at the

smaller ends of the cones, and by the use of the baffle 5 the tendency of air or gas introduced at the inlet 7 of the lower cone to follow the shaft and escape at the inlet 6 at the top of the upper cone is prevented, the baffle acting to arrest and divert the air or gas and cause it to enter and discharge with the meeting streams of liquid from the two cones.

The form shown in Fig. 2 differs from Fig. 1 merely in the dimensions of the two cones 8 and 9, these being of different lengths and different diameters at the discharge end with the baffle 5 placed midway between the discharge ends, and performing the same function as described in connection with the form shown in Fig. 1.

In Fig. 3, a slight difference is shown in the dimensions of cones 10 and 11, they being of equal length from end to end, but of different diameters. The reason for these differences in form and dimension of the cones in Figs. 2 and 3, is to create a differential in the speed of outflow from the discharge ends of the cones to insure the meeting of different particles of the circulating mass at the discharge area between the two cones where the material issues at different speeds.

In the form shown in Fig. 4, the cones 12 and 13 are of uniform size, and two baffles 14 and 15 are employed, one being located in each cone instead of the single baffle 5 located equidistantly between the discharge ends of the cones.

In the form shown in Fig. 5, the cones 16 and 17 are of uniform dimensions, and the baffles 18 and 19 are of convex-concavo form, their concavities facing each other, and they are shown located partly within and partly without the discharge ends of the cones.

In Fig. 6, the cones 20 and 21 are of uniform dimensions and the baffles 22 and 23 are cone-shaped, and located within the cones 20 and 21, respectively.

In the form shown in Fig. 7, the cones 24 and 25 are of uniform dimensions and the baffle 26 is in the form of a double cone, centrally located on the shaft 2.

In the several combinations of cones and baffle or baffles, it is not the intention to be limited as to selection of type and dimension of cone or cones, baffle or baffles, but the several different selections shown and described are merely illustrative of the fundamental idea of the invention, which is the use of a baffle or baffles of any form located on the shaft at or near the discharge ends or within the area of the cones of any relative dimensions.

It may be desirable to make various changes, and even resort to some not illustrated, in the treatment and mixing of, different liquid and semi-solid substances, all of which are considered within the scope and breadth of this invention, the particular form of baffle employed and its location with respect to the cones always serving the purpose of diverting the course of the material treated including air or gas in order to insure that the entire outflow shall be in one discharging stream peripherally at the opposed enlarged ends of the cones.

I claim:

1. A revolving cone mixer including a tank, a rotary shaft, cones secured to the shaft with their larger ends discharging toward each other

and having inlets at their remote outer ends, and at least one baffle located on the shaft within the general area bounded by the two cones, said baffle having smooth and unobstructed surfaces and being of less diameter than the mean diameter of said cones.

2. A revolving cone mixer including a tank, a rotary shaft, cones secured to the shaft with their larger ends discharging toward each other and having inlets at their remote outer ends, and a baffle carried by the shaft at a point equidistant between the discharge ends of the cones, said baffle having smooth and unobstructed surfaces and being of smaller diameter than the mean diameter of said cones.

ELVIN M. UNDERWOOD.
